DISSIPATIVE LOAD

Benjamin Whitfield Griffith, Jr., Dallas, Tex., assignor to Continental Electronics Manufacturing Company, Dallas, Tex., a corporation of Texas

Application October 9, 1953, Serial No. 385,071

6 Claims. (Cl. 333—22)

The present invention relates to dissipating transmission lines to dissipate radio frequency energy, and more particularly to dissipative transmission lines of high power handling capacity.

In the design of dissipative transmission lines, it is often necessary to effect a compromise between power handling capacity, voltage handling capacity, and physical size of the line. Decreasing the spacing between conductors decreases the characteristic impedance and the sending end impedance of the line and, with a given material to dissipate energy, increases the attenuation of the line. However, the possibility of voltage breakdown between the conductors of the line is increased, and therefore the voltage capacity of the line decreased. If the voltage handling capacity is important, the line may have to be extended to undesirable lengths to obtain sufficient power handling capacity.

It is accordingly an object of the present invention to decrease the physical size of dissipative transmission lines having a certain power and voltage handling capacity.

It is another object of the present invention to increase the voltage handling capacity of dissipative transmission lines without increasing the size thereof.

With the above objects in view, the invention relates to dissipative transmission lines, adapted to be connected to a source of radio frequency energy, which are characterized by a pair of substantially similar transmission lines of equal length, each having one end adapted to be connected to the source of energy so that they are connected in parallel; the other end of one of the lines of the pair is short circuited, while the other end of the other line (of the pair) is open circuited. The result of this connection is that the sending end impedance for a thus connected line (one open, the other short circuited) will be identical with the sending end impedance of a line which is short circuited at the far end, and which is twice as long as either of the pair of lines.

It is to be noted that the total length of line, or wire, necessary is not changed. However, when the one-open, one-short circuited method of connection of two lines in parallel is being used, each of the pair of lines may have twice the characteristic impedance as the characteristic impedance of a single, long line when a given sending end impedance is desired; this, in turn permits greater spacing between conductors, and therefore improves the voltage handling capacity. Further, it is often easier to physically arrange two lines next to each other rather than as a single, long line.

The invention is not limited to any particular kind of dissipative transmission line; it might be an open wire line consisting of stainless steel wire, a coaxial line containing a purely resistive element as the central conductor, or it might be constructed with a resistive element comprising a large number of finely dispersed ferromagnetic particles surrounding a conductor, such as more fully described and claimed in my copending application Serial No. 386,034 filed Oct. 14, 1953.

In the accompanying drawing I have illustrated two

examples of connecting the pair of lines to a source of energy.

Figure 1 is a schematic diagram of a pair of dissipative lines connected according to the invention.

5 Figure 2 is a schematic diagram of a balanced pair of co-axial dissipative lines connected to the source of R.F. energy.

Referring now to the drawings, and more particularly to Fig. 1, 10 schematically designates a source of R.F.

10 energy having output leads 11 and 12. The dissipative transmission line is shown, for purposes of illustration, as an open wire line, for example of steel wires composing component lines A and B, each line consisting of wires 13 and 14, and 15 and 16. Wires 13 and 14 form together 15 one of the pair of dissipative transmission lines, and wires 15 and 16 form the other one of the pair. Wires 13 and 14 (component line A), as well as wires 15 and 16 (component line B) are connected to leads 11 and 12 at one of their ends. At the other end, the component line A 20 (wires 13, 14) is short circuited, as shown at 17. The other end of component line B (wires 15 and 16) is open circuited as shown at 18.

Fig. 2 illustrates a pair of co-axial dissipative lines connected to a load so that the connection is balanced

25 with respect to ground. The source of R.F. energy, 10, is connected to a center tapped transformer, 20; the center tap is connected to ground in a manner well known in the art. One side each of the transformer 20 is connected to the center conductors 21, 22, 23 and 24 of co-axial

30 dissipative transmission line components C, D, E and F, the outside conductors 25, 26, 27 and 28 being grounded as shown in the drawing. The center conductor preferably is a resistive element, for example, a carbon rod. The four line components C, D, E and F should be 35 as alike to each other as possible, to obtain a good balance. Two lines, C and D, and E and F, respectively, form a pair connected in parallel. One line of the pair, here shown to be lines C and E are short circuited at the end removed from the connection to the power 40 source; the other line, of each pair, here shown as lines D and F, is open circuited.

It is of course obvious that the co-axial lines may also be replaced by open wire dissipative lines, or any other dissipative line; the particular type of dissipative 45 line is of no consequence, and the operation of the system is independent of the type of line.

MATHEMATICAL CONSIDERATIONS

50 Definition of symbols used:

Z_0 —characteristic impedance of one component of line (A or B, Fig. 1)

Z_{sc} —sending-end impedance of short circuited component of line

Z_{oc} —sending-end impedance of open circuited component of line

Y_0 —characteristic admittance of one component of line

Y_{sc} —sending end admittance of short circuited component of line

Y_{oc} —sending end admittance of open circuited component of line

L —length of each line

α —propagation function of each line, equal to $\alpha_1 + j\alpha_2$

Y —admittance at junction of two transmission lines, the sending end terminals of which are connected in parallel

Z —impedance at junction of two transmission lines, the sending end terminals of which are connected in parallel

70 Sending end impedance of a single short circuited transmission line:

$$Z_{sc} = Z_0 \tanh \alpha L$$

Sending end impedance for a single open circuited line:

$$Z_{oc} = Z_0 \coth \alpha L$$

Sending end admittance of single, short circuited line:

$$Y_{sc} = \frac{1}{Z_{sc}} = Y_0 \coth \alpha L$$

Sending end admittance of single open circuited line:

$$Y_{oc} = \frac{1}{Z_{oc}} = Y_0 \tanh \alpha L$$

Connecting two lines, one open circuited, and one short circuited, in parallel, the sending end admittance will be:

$$\begin{aligned} Y &= Y_{sc} + Y_{oc} \\ Y &= Y_0 \coth \alpha L + Y_0 \tanh \alpha L \\ Y &= Y_0 (\coth \alpha L + \tanh \alpha L) \end{aligned}$$

Since: $\coth \theta + \tanh \theta = 2 \coth 2\theta$; and substituting: $Y = 2Y_0 \coth 2\alpha L$; then the sending end impedance will be:

$$Z = \frac{1}{Y} = \frac{1}{2} Z_0 \tanh 2\alpha L$$

In comparison, two short circuited lines in parallel have a sending end impedance of $\frac{1}{2} Z_{sc} = \frac{1}{2} Z_0 \tanh \alpha L$.

It is therefore seen that the sending end impedance function for the line connected with one open circuited, and one short circuited component will be that of a transmission line twice as long having two short circuited components in parallel; in other words, the decrease in the input impedance of the line (as seen from the sending end) by parallel connection is still obtained by the parallel connection of one open, and one short circuited line with the one open, one short circuited connection; however, the deviation of the sending end impedance from the value of $\frac{1}{2} Z_0$, resulting from the non-infinite length of the line, will be much less where one line component is short circuited and one open circuited than where both line components are short circuited or both open circuited.

I claim:

1. In a system of high frequency transmission lines, a broad frequency band resistor comprising a pair of line components of substantially equal lengths, said pair being connected in parallel at one end thereof; one line component being open circuited at the other end, and the other line component being short circuited at the other end, each of said line components including a conductor formed of a resistive material.
- 5 10. 2. A system according to claim 1, wherein the resistive material is a stainless steel wire forming one conductor of each line component.
- 15 3. A system according to claim 1, wherein each line component includes a conductor and finely dispersed ferromagnetic material surrounding said conductor.
- 20 4. A system according to claim 3, wherein each line component is a coaxial line and said ferromagnetic material surrounds the inner conductor of said coaxial line.
- 25 5. A system according to claim 1, wherein each line component includes a pair of conductors formed of a resistive material.
- 30 6. In a system of high frequency transmission lines, a broad frequency band resistor comprising a pair of line components of substantially equal lengths, said pair being connected in parallel at one end thereof; one line component presenting at the parallel connected end an impedance corresponding to open circuit condition, and the other line component presenting at said parallel connected end an impedance corresponding to short circuit condition, each of said line components including energy dissipating means for dissipating most of the energy supplied to said line components.
